CLAIM

The ornamental design for a battery terminal clamp, as shown and described.

DESCRIPTION

FIG. 1 is a top, left perspective view of a battery terminal clamp showing my new design;

FIG. 2 is a right side view thereof;

FIG. 3 is a left side view thereof;

FIG. 4 is a top plan view thereof;

FIG. 5 is a bottom plan view thereof;

FIG. 6 is a front elevational view thereof; and,

FIG. 7 is a rear elevational view thereof.

The phantom battery and battery terminal portions illustrated in FIG. 1 do not form a part of the claimed invention.
